UNITED STATES PATENT OFFICE.

HARRY A. GOLLOBIN, OF NEW YORK, N. Y.

REMOVABLE BRIDGE FOR TEETH.

Application filed June 16, 1922. Serial No. 568,751.

To all whom it may concern:

Be it known that I, HARRY A. GOLLOBIN, a citizen of the United States, and resident of the borough of Bronx, in the city and 5 State of New York, have invented a new and useful Improvement in Removable Bridges for Teeth, of which the following is a specification.

This invention relates to certain improvements in bridges for teeth and has more particularly for its object to provide novel means for attaching removable bridges to abutments in the mouth in such a manner that the bridges will be held very rigidly by 15 frictional engagement with the said abutments.

This invention furthermore relates to certain improvements in the construction, form and co-relation of the frictional coacting 20 bridge and abutment members of the attachment for removably securing the bridge in the mouth.

Practical embodiments of my invention are represented in the accompanying drawings, in which—

Fig. 1 represents in plan the removable bridge located in proper position in the mouth.

Fig. 2 represents a detail section on the 30 line II—II of Fig. 1.

Fig. 3 represents a plan of the first form of abutment member.

Fig. 4 represents a section on line IV—IV of Fig. 3.

Fig. 5 represents a plan of the corresponding bridge member.

Figs. 6, 7 and 8 represent sections on lines VI—VI, VII—VII, and VIII—VIII respectively of Fig. 5.

Fig. 9 represents a plan of a second form of abutment member.

Fig. 10 represents a section on line X—X of Fig. 9.

Fig. 11 represents a plan of the corresponding bridge member.

Figs. 12, 13 and 14 represent sections on lines XII—XIII, XIII—XIII and XIV—XIV of Fig. 11.

Fig. 15 represents a plan of a third form 50 of abutment member.

Fig. 16 represents a section on line XVI—XVI of Fig. 15.

Fig. 17 represents a plan of the corresponding bridge member.

Figs. 18, 19 and 20 represent sections on 55 lines XVIII—XVIII, XIX—XIX and XX—XX of Fig. 17.

Fig. 21 represents a plan of a fourth form of abutment member.

Fig. 22 represents a section on line 60 XXII—XXII of Fig. 21.

Fig. 23 represents a plan of the corresponding bridge member.

Figs. 24, 25 and 26 represent sections on 65 lines XXIV—XXIV, XXV—XXV and XXVI—XXVI of Fig. 23.

Fig. 27 represents a plan of a fifth form of abutment member.

Fig. 28 represents a section on line 70 XXVIII—XXVIII of Fig. 27.

Fig. 29 represents a top plan view of the corresponding bridge member.

Figs. 30, 31 and 32 represent sections on 75 lines XXX—XXX, XXXI—XXXI and XXXII—XXXII of Fig. 29.

The portion of the mouth represented in the drawing is denoted by 1 and the teeth which form the abutments for the bridge are denoted by 2 and 3. The bridge of teeth for filling the space between the abutment 80 teeth is denoted by 4.

In the present instance I have shown like means for removably attaching both ends of the bridge to the abutment teeth. In all 85 the forms illustrated, the shank 5 of the bridge member is of the desired height, length and thickness and it is provided with a T-head 6. The separate L-shaped spring has its horizontal branch 8 permanently 90 united to the bridge member along the bottom of the shank 5 and head 6, the free vertical branch 9 of which spring extends along the outer face of the head from bottom to top thereof, the said free vertical branch being slightly separated from the head to permit the spring to be forced toward the head when the bridge member is inserted 95 into the corresponding recess in the abutment member to be hereinafter described.

In the first form of attachment illustrated 100 in Figs. 1 to 8 inclusive, the head 6 has its projecting sides rounded from top to bottom as shown at 7, 7. In this form also both the horizontal and vertical branches of the spring are triangular in cross section and 105 the bottom of the shank and head is provided with a groove 10 for receiving the bottom branch of the spring, and the outer face

of the head is provided with a groove 11, forming a seat for the free vertical branch of the spring when the said vertical branch is forced inwardly against the head by the 5 insertion of the head into the recess in the abutment member.

In the form under discussion the abutment member comprises a vertical back wall 12, curved side walls 13, 13 terminating in 10 straight side walls 14, 14; and a bottom wall 16 forming a recess shaped to snugly fit the head of the bridge member.

In the form of attachment as shown in Figs. 9 to 14 inclusive, the bottom and vertical branches of the L-shaped spring are substantially rectangular in cross section, the free vertical branch of the spring extending across the entire outer face of the head of the bridge member, the front side corners of 20 the vertical branch of the spring being rounded to form continuations of the curved sides of the T-head when the spring is forced rearwardly into engagement with the outer face of the head. In this form there are no 25 grooves provided along the bottom of the outer face of the bridge member for receiving the spring, the bottom horizontal branch of the spring being permanently united to the bottom of the shank and head; only the 30 portions of the projecting sides of the head which extend beyond the corresponding sides of the spring being extended downwardly a short distance, as shown at 17, 17, the portions being flush with the bottom in 35 the horizontal branch of the spring. In the form under discussion, the abutment member has its recess shaped to snugly fit to the head of the bridge member.

In the form of attachment as illustrated 40 in Figs. 15 to 20 inclusive, the projecting sides of the head of the bridge member are provided with curved outer edges 18, 18 and sharp inner edges 19, 19, extending from top to bottom thereof. In this form 45 the inner walls of the horizontal and vertical branches of the spring are convex and the grooves along the bottom and outer face of the bridge member are concave to correspond therewith. In the form under discussion, the abutment member has its recess shaped to correspond with the head of the bridge member.

In the form of attachment illustrated in 55 Figs. 21 to 26 inclusive, the projecting sides of the head of the bridge member are shown as having square corners 20, 20 and 21, 21 along its front and back edges from top to bottom thereof, the inner walls of the horizontal and vertical branches of the spring being shaped in this form substantially like the form shown in Figs. 1 to 8 inclusive. In the form under discussion, the abutment member has its recess shaped to snugly fit to the head of the bridge member.

60 65 In the form illustrated in Figs. 27 to 32

inclusive the projecting sides of the head of the bridge member have square corners 22, 22 and 23, 23 along its front and back edges from top to bottom thereof as in the preceding 70 form just described, but in this last form the horizontal and vertical branches of the spring are rectangular in cross section and the outer face of the head is provided with a rectangular groove 24 for receiving the free vertical branch of the spring. 75

In the form under discussion, the abutment member has its recess shaped to correspond with the head of the bridge member.

Inlays for securing the abutment members to their respective teeth are denoted by 25, 80 the shape and size of the abutment members, being such that the vital portion of live teeth when used as abutment teeth may be saved in the cutting of the teeth to properly secure the abutment members in position.

It will be understood that the embodiments illustrated are only a few of the numerous forms in which the bridge and abutment members could be made to suit various requirements but in all of these forms the 90 head of the bridge member is not weakened by kerfs as heretofore, the frictional grip between the bridge and abutment members in the present improvement being provided for by a separate spring permanently united to 95 the bridge member. This arrangement permits the head member and spring to be made of different metals, thus allowing the head member to be made of a hard, strong and rigid metal and the spring to be made of a 100 spring metal, thereby adding great strength to the attachment.

Furthermore, it will be seen that the head may be made of any desired width and the spring may be made of any desired width, 105 thus rendering the attachment applicable for many different conditions. The provisions of a separate spring also enables the free vertical branch of the spring to be adjustable to the minutest degree, to obtain the required frictional engagement between the bridge and the abutment members. The provision of a bottom wall for the abutment member also provides a better and more rigid support for the bridge member. It 115 will also be observed that all strain is removed from the spring, the strain being taken by the head of the bridge member, which has not been weakened by dividing the same to form friction surfaces as here- 120 tofore commonly done.

115 What I claim is:

1. A removable bridge attachment including coacting bridge and abutment members, the bridge member comprising a head and shank, and a separate friction spring having a horizontal branch permanently united to the bottom of the bridge member and a free vertical branch extending along the outer face of the head of the bridge 120

member, the head having a groove along its outer face for permitting the free vertical branch of the spring to be forced thereinto.

5 2. A removable bridge attachment including bridge and abutment members, the bridge member comprising a head and shank, and a separate friction spring having horizontal and vertical branches, the bottom of the bridge member having a groove for receiving and permanently holding the horizontal branch of the spring, the free vertical branch of the spring extending along the outer face of the head of the 10 bridge member.

15 3. A removable bridge attachment including bridge and abutment members, the bridge member comprising a head and shank, and a separate friction spring having horizontal and vertical branches, the bottom of the bridge member having a groove for receiving and permanently holding the horizontal branch of the spring and the outer face of the head having a groove for 20 permitting the free vertical branch of the spring to be forced thereinto.

25 4. A removable bridge attachment including coacting bridge and abutment members, the bridge member having a T-head, and a separate friction spring having a horizontal branch permanently united to the bottom of the bridge member and a free vertical branch extending along the outer face of the head of the bridge member.

35 5. A removable bridge attachment includ-

ing coacting bridge and abutment members, the bridge member having a T-head, and a separate friction spring having a horizontal branch permanently united to the bottom of the bridge member and a free vertical branch extending along the outer face of the head of the bridge member, the head having a groove along its outer face for permitting the free portion of said spring to be forced thereinto.

40 6. A removable bridge attachment including coacting bridge and abutment members, the bridge member having a T-head, and a separate L-shaped friction spring, the bottom of the bridge member having a groove for receiving and permanently holding the horizontal branch of the spring, the free vertical branch of the spring extending along the outer face of the head of the 45 bridge member.

50 7. A removable bridge attachment including coacting bridge and abutment members, the bridge member having a T-head, and a separate L-shaped friction spring, the bottom of the bridge member having a groove for receiving and permanently holding the horizontal branch of the spring, and the outer face of the head having a groove for permitting the free vertical branch of the 55 spring to be forced thereinto.

60 In testimony, that I claim the foregoing as my invention, I have signed my name this 14th day of June 1922.

HARRY A. GOLLOBIN.
